TIMING CIRCUIT

John W. Smith, Cedar Rapids, Iowa, assignor to
 Collins Radio Company, Cedar Rapids, Iowa,
 a corporation of Iowa

Application February 26, 1951, Serial No. 212,827

4 Claims. (Cl. 250—27)

1

This invention relates in general to timing circuits and in particular to control apparatus which has a release time different from the connect time.

It becomes desirable at times to control apparatus such that the starting time does not equal the releasing time. For example, it may be desirable to energize a relay instantaneously upon the closing of a switch and have it remain energized for a predetermined time after the switch is opened. With this arrangement after the relay has once been energized, a very short interruption of the actuating switch will not cause the relay to drop out. Many other applications exist wherein this type of control is desired.

It is an object of this invention, therefore, to provide an apparatus which has a differential between the energization and the deenergization times.

Another object of this invention is to provide an improved timing device which minimizes the load on the electron valves of the apparatus.

Still another object of this invention is to provide an improved fast acting control circuit.

A feature of this invention is found in the provision for a pair of electron valves which are connected such that the closing of a control switch causes instantaneous operation of the controlled device and the opening of the switch causes disengagement of the controlled apparatus after a pre-determined time.

Further features, objects, and advantages of this invention will become apparent from the following description and claims when read in view of the drawings, in which;

The figure illustrates a circuit of this invention.

With reference to the drawing, a first electron valve V₁ has its plate 10 connected in series with a controlled device 11 to a positive direct current voltage. The control device might be, for example, a current sensitive relay with its actuating coil connected in series between the plate 10 and the positive voltage. The cathode 12 of valve V₁ is connected in series with a resistor R₁ to ground.

A second electron valve V₂ has its plate 13 connected to ground and its cathode 14 is connected to the grid 16 of valve V₁. A condenser C is connected between the cathode 14 and ground.

The grid 17 of valve V₂ is connected to a resistor R₂ which has its opposite side connected to the cathode 14. The grid 17 is also connected to the junction of a pair of resistors, R₃ and R₄.

The opposite side of R₃ is connected to a negative direct current voltage and the opposite side of resistor R₄ is connected to ground. A switch

2

S₁ has one side connected to ground and a terminal 18 is connected to the grid 17, so that the grid may be connected and disconnected to ground when the switch S₁ is closed and opened, respectively.

The values of components might be:

R ₁	ohms	1,000
R ₂	do	1,000,000
R ₃	do	100,000
R ₄	do	100,000
C	microfarad	1

The positive voltage connected to the plate 10 through the control device 11 is 250 volts direct current. The negative voltage connected to R₃ is 40 volts direct current.

In operation, suppose that switch S₁ has been open for a relatively long time. Then the voltage E₂ across the resistor R₄ will be 20 volts negative, and the voltage E₁, across condenser C will be almost 20 volts negative. Since the grid 16 of valve V₁ is negative, V₁ will have minimum current or be cut off completely, depending on the tube characteristics. The tube V₂ will also have minimum current and the grid 17 and cathode 14 will be at substantially the same potential. In this condition the control device 11 will have minimum current passing through it and will therefore be unactuated.

30 Assume that switch S₁ is closed. The grid 17 of tube V₂ is immediately connected to ground potential thus becoming positive relative to the cathode 14. This causes the tube V₂ to act as a diode thus very quickly discharging the condenser C to ground potential. The grid 16 of tube

35 V₁ is connected to the condenser C and thus its voltage rapidly goes to ground potential thus allowing the current through tube V₁ to increase almost instantaneously when switch S₁ is closed.

40 The controlled device 11 is actuated. Tube V₁ will continue to conduct as long as the switch S₁ is closed.

Assume that the switch S₁ has just been opened. The tube V₂ will immediately be cut off or have 45 minimum current for the reason that the negative control voltage connected to R₃ will immediately cause E₂ to become negative. The tube V₁, however, will continue to conduct until the condenser C has charged sufficiently to cut it off.

50 The time constant for charging C is determined by the product R₂ C, and since this time constant is chosen to be relatively large, the tube V₁ may continue to conduct for three or four seconds, for example, after the opening of switch S₁. If the switch S₁ is re-closed during this interval the

controlled device II will not be de-actuated during the open period of switch S1. Thus, with a temporary failure of power which is quickly resumed, the controlled device II will not be de-energized.

Although the invention has been described with respect to a preferred embodiment thereof, it is not to be so limited as changes and modifications may be made therein which are within the full intended scope of the invention as defined by the appended claims.

I claim:

1. Control means for a controlled device comprising, a first electronic valve which has its plate connected in series with the controlled device to a positive direct current voltage and its cathode connected in series with a first resistor to ground, a second electronic valve with its plate connected to ground and its cathode connected to the grid of the first electronic valve, the grid of the first electronic valve connected to one side of a condenser which has its opposite side connected to ground, a grid leak resistor connected between the grid and cathode of the second electronic valve, a voltage divider comprising third and fourth resistors connected in series between ground and a negative direct current voltage, the grid of the second electronic valve connected to the connection point between said third and fourth resistors, and switching means for connecting said connection point to ground.

2. Control means for obtaining a fast attack time and a slow release time in a controlled device comprising, a first electron valve with the controlled device connected in its plate circuit in series with a positive direct current voltage, a second electron valve with its cathode connected to the grid of the first electron valve, a capacitor connected to the cathode of the second electron valve and its opposite side connected to ground, a grid leak resistor connected between the grid of the second electron valve and the cathode, a voltage divider comprising a pair of resistors connected in series between ground and a negative direct current voltage, the grid of said second electron valve connected to the mid-point between said first and second pair of resistors, a controlling switch connected to ground and movable to connect the mid-point between the pair of resistors to ground.

3. A control circuit for instantaneously energizing a controlled device and de-energizing said controlled device only after a pre-determined time comprising, a first electron valve with its plate connected in series with said controlled device to a positive direct current voltage, a first resistor connected between ground and the cathode of the first electron valve, a second electron valve with its plate connected to ground and its cathode connected to the grid of the first electron valve, a capacitor connected to the cathode of said second electron valve and its opposite side connected to ground, a second resistor connected between the grid and cathode of the second electron valve, third and fourth resistors connected in series between a negative direct current voltage and ground, the grid of the second electron valve connected to the junction between the third and fourth resistors, and switching means with a movable throw arm connected to ground and movable to engage the junction point between the third and fourth resistors.

4. A control device with a fast attack time and a slow release time for a controlled device comprising, a first electron valve, a second electron valve with its cathode connected to the control grid of the first electron valve, a charging circuit comprising a resistor and condenser connected to the cathode of said second electron valve, a voltage divider comprising a pair of resistors connected between a negative direct current voltage and ground, the grid of said second electron valve connected to said voltage divider, switching means for connecting the mid-point between said pair of resistors to ground, and said first and second electron valves having minimum current when said switching means is open and maximum conduction when said switch is closed.
